DESIGN FOR AN EMBROIDERED LACE MEDALLION

Henry Schwarber, Weehawken, N. J.

Application December 23, 1941, Serial No. 104,814

Term of patent 3½ years

To all whom it may concern:

Be it known that I, Henry Schwarber, a citizen of the United States of America, residing at Weehawken, in the county of Hudson and State of New Jersey, have invented a new, original, and ornamental Design for Embroidered Lace Medallion, of which the following is a specification, reference being had to the accompanying drawing, forming part thereof.

The figure is a plan view of an embroidered lace medallion, showing my design.

I claim:

The ornamental design for an embroidered lace medallion, as shown.

HENRY SCHWARBER.
